UNITED STATES PATENT OFFICE.

ANTON KALOSKY, OF NEW BRITAIN, CONNECTICUT.

CURTAIN AND SHADE-ROLLER SUPPORTER.

1,086,919.

Specification of Letters Patent.

Patented Feb. 10, 1914.

Application filed August 7, 1913. Serial No. 783,531.

To all whom it may concern:

Be it known that I, ANTON KALOSKY, a citizen of the United States, residing at New Britain, in the county of Hartford and State 5 of Connecticut, have invented certain new and useful Improvements in Curtain and Shade-Roller Supporters, of which the following is a specification.

My invention relates to improvements in 10 curtain and shade roller supporters, and the object of my improvement is simplicity and economy in construction and convenience and efficiency in use.

Figure 1 is a front elevation of my improved curtain and shade roller supporter, and a shade roller, a curtain rod and part 15 of a window casing. Fig. 2 is an end view on an enlarged scale of the left supporting device, and a curtain pole in cross-section. Fig. 3 is a view from the other end of the 20 right supporting device. Fig. 4 is a front elevation of the left supporting device. Fig. 5 is a similar view of the right supporting device. Fig. 6 is a bottom view of 25 the right supporting device. Fig. 7 is a similar view of the same on an enlarged scale and in part broken out. Fig. 8 is a similar view of a modification of my device. Fig. 9 is an end elevation of the same. Fig. 30 10 is a view corresponding to Fig. 8 of another modification of my device. Fig. 11 is a plan view of a portion of the blank for the same.

My curtain and shade roller supporter 35 comprises a pair of supporting devices A, one of which serves as a left supporting device and the other as a right supporting device, and which devices are suitable for supporting a shade roller B and a curtain pole 40 C. The supporting device A comprises a front plate 15 and a back plate 16 formed of sheet material at right angles one to the other at one of the ends of the front plate 15, the front plate extending laterally, and 45 the back plate 16 extending vertically and at the rear of the front plate 15. The front plate 15 is provided with a longitudinally extending slot 17 separating ways 18. Engaged with the ways 18 is the supporting 50 arm 19 of a shade roller holder 20 on one face and a clamping plate 21 on the other face connected by a clamping screw 22. The shade roller holder 20 is of ordinary construction. The ways 18 are positioned 55 forwardly relatively to the casing so as to provide clearance between the said ways and

casing E as shown at 23 for the clamping means for clamping the shade roller holder in the position in which the same may be adjusted. I support the ways 18 in the forward position so as to provide the clearance mentioned in the following manner: At the inner end the front plate is bent inwardly as shown at 24 to provide a turned edge or apron 25 of sufficient depth to provide the 60 necessary clearance at the said inner end. The said inner end 25 may be further extended laterally to provide a supporting foot 26 and which is provided with a screw hole 27 for a supporting screw. At the outer end 70 I provide proper clearance for the front plate 15 by using a back plate 16 of suitable thickness, and being positioned at the rear of the said outer end. The said back plate thus serves as a supporting foot for the said 75 outer end and thereby provides the clearance desired. The front plate 15 and back plate 16 are connected together by rivets 28. The back plate 16 is formed of a strip of sheet material and comprises a body portion 80 29 which is connected to the front plate 15 in the manner described and as shown extends across the same and is provided with screw holes 30 for supporting screws, one above the other below the front plate 15. 85 At the upper end of the body portion 29 there is a forwardly extending arm 31 provided at the front end with a hook or loop 32 suitable for receiving and supporting the curtain pole C. Accordingly, as described, 90 the back plate 16 serves as the support for the curtain pole and also as the support for the outer end of the front plate 15. And the said front plate 15 constitutes the supporting base for the shade roller holder, and 95 the said back plate 16 and the front plate 15 are formed of strips of sheet material that are rigidly connected together.

In the modification shown in Fig. 8 the supporting foot 26 at the inner end is dispensed with and in lieu thereof the prong 26^a is provided and which is suitable to be driven into the woodwork of the casing E.

In the modification shown in Figs. 10 and 11 the prong 26^b is provided at the inner end 100 of the slot 17 and from material that would otherwise be cut away in forming the said slot.

In the modifications described the prongs 26^a and 26^b enter the woodwork sufficiently 105 to serve to support the inner end of the front plate 15^a or 15^b as the case may be

and the screws engaged with the holes 30 serve to hold the said prongs positively engaged with the said woodwork.

I claim as my invention:—

- 5 In a curtain and shade roller supporter having a plate for receiving a shade roller holder and having the portion on which the said shade roller holder is mounted spaced from the window casing suitably to house
- 10 between the said portion and the said casing a part of the said holder and clamping means therefor, and the said plate consisting of a laterally extending strip of sheet metal, the body portion of the said strip being provided with means for adjustably re-
- 15 ceiving the said holder, the inner end of the said strip being off-set rearwardly to provide the proper spacing at the said inner end, and a back plate being positioned between the outer end of the said strip and 20 the said casing, and the said back plate being of sufficient thickness to properly space the said outer end of the strip and the said back plate being also provided with means for supporting a curtain pole.

ANTON KALOSKY.
